UNITED STATES PATENT OFFICE

ALFONSO SGRITTA, OF BROOKLYN, NEW YORK

AUTOMATIC WICK THREADING MACHINE

Application filed October 11, 1928. Serial No. 311,766.

This invention relates to candle making machinery and has particular reference to a device for threading wicks into candles or similar articles.

- 5 One object of the invention is to provide a device of the character described having improved means to properly and accurately center the candles for efficient and expeditious threading thereof.
- 10 Another object of this invention is to provide a device of the type set forth having improved means for feeding candles and automatically passing the wick thereinto, and severing and clinching the wick.
- 15 Another object of the invention is the provision of a device of the nature specified having comparatively few and simple parts and which is relatively inexpensive to manufacture, compact and rugged in construction, and reliable and efficient in use to a high degree.

A further object of the invention is to provide an improved candle or similar article having novel coordination with the 25 device for improved operation.

Other objects and advantages of the invention will become apparent as the specification proceeds.

With the aforesaid objects in view, the 30 invention consists in the novel combinations and arrangements of parts hereinafter described in their preferred embodiments, pointed out in the subjoined claims, and illustrated on the annexed drawings, where- 35 in like parts are designated by the same reference characters throughout the several views.

Figure 1 is a view in front elevation of a machine embodying the invention.

- 40 Fig. 2 is a side elevation of the same.
- Fig. 3 is a top plan view of the machine.
- Fig. 4 is an enlarged fragmentary vertical section of the table of the machine and associated mechanism.

45 Fig. 5 is a bottom plan view of the parts shown in Fig. 4.

Fig. 6 is a view in vertical section taken on line 6—6 of Fig. 4.

50 Fig. 7 is a view in vertical section taken on line 7—7 of Fig. 4.

Fig. 8 is an enlarged horizontal sectional view of the automatic motor switch.

Fig. 9 is a fragmentary view in elevation of the machine looking at the left of Fig. 3.

Fig. 10 is an enlarged vertical section 55 taken on line 10—10 of Fig. 9.

Fig. 11 is an enlarged horizontal section taken on line 11—11 of Fig. 1, with certain parts removed.

Figs. 12 and 13 are enlarged vertical sec- 60 tional views taken on lines 12—12 and 13—13 respectively of Fig. 11.

Fig. 14 is a bottom view of the hammer head.

The advantages of the invention as here 65 outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as 75 showing the preferred exemplification of the invention.

Generally described, the invention provides a machine having a substantially circular plate or table that is rotatable about a 80 vertical axis. The plate has a series of perforated dies or forms disposed on the upper surface thereof in proximity to its edge. The dies are so shaped as to conform accurately to the upper surface of the articles 85 or candles to be threaded to properly center the same automatically, when the candles are placed in inverted position on the dies. As the feed table rotates, each of the dies is successively brought with its perforation 90 into registry with a wick supplying device that moves a predetermined length of wick into the candle. By this invention, the candles used have countersinks to guide the wick thereinto. At the bases of the candles 95 as used herein are secured wick clips, accurately centered, through which the wick readily passes. A hammer serves to strike the prongs in the clips to clinch the projecting end of the wick and to flatten down the 100

said end on the clip. The correct length of wick is supplied to each candle by means of a pair of automatically operated rollers. In this invention, while the table turns, the 5 hammer moves upward. Then the table comes to a stop, while the feeding rolls begin to thread the wick into a candle, the hammer in the meantime moving slowly downward. When the hammer strikes, as 10 aforesaid, a knife beneath the rotating table cuts the wick leaving just enough to project at the top of the candle in the usual manner. A unitary drive mechanism operates all parts of the machine. The table is 15 turned by a simplified pawl and ratchet arrangement, which requires very little power. The said arrangement is also adjustable to permit the perforations in the dies to aline with the wick feeding means. The rollers 20 are adjustable as to the length of wick fed, and can be released at will. The hammer includes a novel feature that prevents cutting of the projecting flattened portion of the wick. Means is provided to automatically 25 receive the finished candles and discharge the same into a suitable receptacle. Should the wick become tangled a switch opens and throws the motor out of circuit. A simple pedal device permits the machine 30 to be momentarily disconnected by opening a clutch. The drive includes a pair of alined shafts compactly coacting to drive the various machine parts.

It will be appreciated that while the 35 invention has been shown as designed particularly for use in the manufacture of night candles, that it is capable of being modified for many other purposes, the candle being conceived of as any member having an 40 opening, and the wick as a member inserted into said opening.

This invention is intended particularly for use in conjunction with my automatic night candle molding machine as shown and 45 described in my application for Patent Serial No. 303,196 filed August 31, 1928.

Referring in detail to the drawing 15 denotes a device embodying the invention. The same includes a frame having a base 50 member 16, upon which rest the corner standards 17 to 20 and which are integrally connected in pairs by means of horizontal flanges 21. Supported on the latter is a table plate 22 which is substantially flat 55 throughout, except for an edge or rim flange 23. The table plate is secured to the flanges by bolts 24.

Mounted on the base member 16 is a motor 25 which is connected into an electrical circuit by a lead 26. The latter connects with an automatically operated switch 27 mounted on a bracket 28. The purpose of this switch is to break the motor circuit if the wick is knotted or tangled, and the construction of the switch will be hereinafter de-

scribed. A main switch 29 is provided whereby the operator may start or stop the machine, the switch 29 being connected by a lead 30 in series with the automatic switch 27. A main lead 31 supplies current to the 70 switch 29.

Driven by the motor 25 is a pinion 35, the teeth of which mesh with those of a gear wheel 36, which is mounted on a counter shaft 37 that is journaled in a bearing 38. Secured to the countershaft is a sprocket 75 wheel 39 which is interconnected by a chain 40 with a speed reduction sprocket wheel 41. The latter is freely rotatable on a horizontal shaft 42 which is journaled in a bearing 43 that is disposed in relative proximity to the table plate 22.

Operatively connecting the shaft 42 with the sprocket wheel 41 is a clutch 45 which is normally in locked position. Said clutch includes a sleeve 46 which is keyed to the shaft at 47. Formed in said sleeve in a direction parallel to the axis thereof is a recess 48, which is closed at one end by a stop member 49. Slidably mounted on 90 said recess is a bolt 50, an end of which is adapted to engage the sprocket wheel 41 in one of the four slots 51 therein. Normally urging the bolt out of locking engagement is an expansion coil spring 52, 95 that is positioned in a lengthwise extending recess 53 in the bolt. One end of the recess 53 is closed to engage the said spring and the other end of the recess is open to receive a projection or finger 54 of a collar 55 100 that is secured to the sleeve 46 by a set screw 56. To move the bolt into locking engagement a ring member 57 is mounted on the sleeve 46 for sliding movement in an axial direction, said ring member having 105 an annular inclined cam face 58. The latter is adapted to be engaged by a member 60 that is moveable in a vertical plane toward and from the axis thereof. The member 60 constitutes the end portion of an arm 110 61 that is pivotally mounted at 62. Operating the arm 61 is a lever 65 that is pivotally mounted at one end at 66, and has its other end formed to constitute a pedal 67. Connecting the lever and the arm is a rigid link 68, which movably engages the same at 69 and 70 respectively. A tension coil 115 spring 71 tends to raise the lever and to move the arm 61 into the dotted line position to throw the bolt 50 into locking coaction. Should it be desired to momentarily stop the machine, it is merely necessary to depress the pedal 67 permitting the spring 52 to retract the bolt. If the machine is to 120 be stopped for a longer period, a pin 72 is inserted into a proper opening therein through a bracket 73, which serves also to limit the downward movement of the lever 65. A smooth operation of the machine 125

may be effected by a flywheel 74 which may also act as a pulley.

In alined relation with the shaft 42 is a shaft 75 that is journaled in a bearing 76. 5 Both of the shafts 42 and 75 have their inner ends in spaced relation to each other and in proximity to the central plane of the machine.

At the inner ends of said shafts are disks 10 77 and 78 which are interconnected by an offset shaft 79, forming a crank for a purpose hereinafter described. Accordingly the shafts 42 and 75 rotate in unison. At the other end of the shaft 75 is secured a disk 15 80, which carries a channel member 81 having a slot 82 in the web 83 thereof. Engaging in the slot 82 is a pin 84 of a pitman 85. The latter eccentrically engages a gear 86 to turn the same. The said gear is mounted 20 at a side of the machine on a stub shaft 87, which is journaled in a bearing 88. Meshing with the teeth of the gear 86 are the teeth of a rack bar 90, which is carried by a bracket 91 for movement in a plane extending 25 from the front to the rear of the machine. The said rack is carried for sliding movement by channel bar 92, within the hollow of which the rack is secured by screws 93. The arms of the channel bar 30 are slidingly received in guide recesses 94 of the bracket 91. Retaining the channel bar in the recesses 94 are a plurality of yokes 95, which are fastened to the bracket 91 by screws 96. To regulate the downward pressure 35 sure on the bar 93, set screws 97 are threaded through the webs of the said yokes to bear on the said bar.

It is thus clearly apparent that the gear 87 is given a to and fro rotation by the pitman 85, thus causing a reciprocatory movement of the rack 90, and the channel bar 92.

Mounted on the channel bar 92 is a pawl 98 having a vertical pivot 99, and actuated 45 in a counterclockwise direction by a leaf spring 100 on the bar 92.

A movable candle feed table 101 is supported on the plate 22 for rotation about a vertical axis. The said plate is provided at 50 a rear-center thereof with a disk 102 resting on the upper side of the plate and secured thereto by a central screw 103 and coacting tapered pins 104. Formed along the periphery of said disk 102 is a recess 105 that constitutes a bearing for the feed table 101. The latter is retained therein by a circular bottom flange 106 of a main upstanding bracket 107. The said flange seats in a circular recess 108 in the upper side of the feed table, and is engaged with the bearing disk 102 by screws 109.

The feed table 101 constitutes in effect a ratchet wheel, the teeth 110 of which are 65 engageable by the pawl 98. Accordingly

the reciprocation of the rack 90 causes a step by step rotation of the feed table.

Brake means 115 for the feed table are provided on opposite sides of the center thereof. Each of said means comprises a horizontal bar 116 carrying at its outer end a roller 117, while near the inner end thereof is a tension member in the nature of a bolt 118, and at the inner end referred to is a bearing screw 119, whereby the downward pressure of the roller 117 can be regulated. 75

To properly carry the candles, the feed table 101 is provided with means 120 for carrying the candles in inverted position, this being found most efficient for accurately 80 centering the candles. According to my copending application for patent, the night candles are molded with their upper ends of a marked angular ornamental conformation. By this invention, the means 120 includes dies 121 whose upper surfaces accurately conform to the upper ends of the candles, whereby the latter are correctly centered for the wick threading operation. Each die is set into a recess 122 in the feed table, and is centrally perforated at 123 to permit the wick to pass therethrough and into the candle. The feed table has a slightly larger opening 124 alining with 123. Since the centers of the dies 121 lie along a circle whose center coincides with the axis of the feed table, the rotation of the latter causes a uniform angular feed of the candles positioned on the dies. 95

The wick 125 is supplied from a reel 126 that is centrally positioned in the frame of the machine and beneath the shafts 22 and 75. Said reel is mounted on a shaft 127 which is journaled in the side portions of the machine frame, and to which it is secured by a set screw 128. At one end of the shaft 127 is a wheel 129 with which coacts a brake 130 that is urged into engagement with the wheel by a spring 131, thus serving to prevent the reel from overrunning. 110

To guide the wick into a die 121 a vertical tube 135 alined therewith is provided, at the front of the machine and in the central plane thereof, the upper end 136 of which is tapered, and the adjacent portion threaded at 137 into a plate 138. The said plate is supported by a bolt 139, the upper end of which is screwed into an oblong plate 140. The same is set into the recesses 141 that are provided along the side edges of a slot 142 in the top plate 22 of the machine frame. While the plate 140 extends to the front of the machine, its rear edge 144 is in spaced relation to the end 145 of the said slot providing an open space 146 for a purpose hereinafter set forth. Securing the plate 140 in fixed position are screws 147. After leaving the tube 135, the wick is passed through an alined guide consisting 130

of a helical wire coil 148, which is supported at its lower end by a laterally projecting portion 149 that is received in a hole 150 in a stud 151 mounted on the plate 140, a set screw 152 serving to clamp the portion 149.

5 The upper end of the spring 148 may bear against a die member 153 that is set into the plate 140, and has a hole 154 to permit the wick to move upward into a candle carrying die 121.

10 To feed the wick, a plurality of wheels 160, and 161 are provided. These wheels make tangent contact so as to be adapted to grip the wick therebetween. The space that 15 may be observed in Fig. 7 between the tube and coil guide 135 and 148 provides a wick portion that is adapted to be gripped by the wheels, the tapered portion of the tube guide extending into close proximity to the 20 point of tangency of the wheels. The wheel 160 is mounted on shaft 162, the axis of which is stationary. The said shaft is journaled for rotation in a plurality of spaced arms 163 and 163a, that extend downward 25 from the plate 140, and is also journaled in a bracket 164 extending from the upper portion 22 of the machine frame. For compactness, the arms 163 and 163a may be set into an opening 165 in the frame portion 30 referred to. Between the said arms is received the wheel 160. Into the shaft 162 is fixed a pin 168, and the arm 163a is recessed at the bearing at 170 to permit the passage of said pin, while the wheel 160 has 35 a keyway 171 to receive the said pin. A collar 172 fixed on end of the shaft 162 serves to prevent endwise movement of said shaft.

40 The wheels 160 and 161 are provided with rubber rings 160a along their peripheries to properly grip the wick without removing therefrom the wax that stiffens the same, and rotation of the wheel 160 as hereinafter described will thus cause a corresponding 45 rotation of the idler wheel 161.

To rotate the wheel 160 periodically and to the proper predetermined extent for the required amount of wick to be fed to a candle, a wheel 175 is journaled for free rotation 50 on the shaft 162. Disposed in proximity to the wheel 175 is a ratchet wheel 176, that is pinned to the shaft at 177. A plurality of pawls 173 are mounted on the independently movable wheel 175, these pawls 55 being retained in engagement with the ratchet wheel by leaf springs 174 mounted on the said wheel 175. Thus a two and fro rotation of the wheel 175 causes a periodic rotation of the ratchet wheel and hence of 60 the shaft 162, with a periodic feed of wick to the candles.

To cause the oscillatory rotational movement of the wheel 175, a channel guide 178 is engaged with the same. The said channel 65 guide is formed with a slot 179 in the

70 web thereof, in which slot the shaft 162 is adapted to be received. A screw 180 serves to fixedly secure the guide 178 to the wheel 175. A washer 181 may be placed between the guide 178 and the bracket 164.

75 Coacting with the guide 178 is a pitman 182, the head of which is formed with a wrist pin 183 that is movably engaged in the slot 179. The pitman also connects with an arm 184 of an annular cam follower 185. The latter includes a plurality of members 186, 187 which are interconnected by bolts 188. The internal surface of the follower is channel shaped to receive a cam 189 that is secured to the shaft 42.

80 By adjusting the position of the pin 183 in the slot 179, the length of wick that is fed to a candle can be regulated. To prevent the wheel 160 from overrunning, a friction brake 190 coacts therewith.

85 The wheel 161 is mounted on a shaft 191 that takes through brackets 192 secured to the plate 140. These brackets are formed with slots 193 in which the shaft 191 is journaled. Pins 194 in the brackets, actuated by individual leaf springs 195, tend to move the shaft 191 to cause the wheels to snugly grip the wick. To release the wick in the event of trouble, plates 196 at the 90 sides of the wheel 161 engaging the shaft 191, are movable in unison by a bar 197. The latter is of L-form, the shorter arm 198 thereof engaging the members 196 in holes therein, while the longer arm is slidingly retained by guides 199. For convenient release of the wheel 161, the bar 197 extends to the front of the machine where it is pinned at 200 to a lever 201 that is pivotally mounted at 202. Thus, on moving the lever 201 toward the machine, the wheel 161 is 100 released.

105 Should the wick be tangled or knotted as it leaves the reel, as shown at 205, the switch 27 functions, as aforesaid, to throw the motor 25 out of circuit. For this purpose the 110 said switch includes a pair of spaced contact elements 206 and 207 mounted in a casting 208. A switch member 209 has pivotal connection with the element 207 and sliding contact engagement with the other element. 115 For operating the switch member, an arm 210 is secured thereto, and extends out of the casting through an open end thereof. The arm terminates in a centrally slotted portion 211, and the wick passes through the 120 slot. Since the slot is just wide enough to receive the wick, a knot 205 will not pass therethrough, but will throw the switch arm upward with the movement of the wick, causing the switch to open.

125 After the requisite length of wick has been supplied to the candle, the wick is severed, leaving a sufficient length thereof projecting from the candle to permit the same to be easily lit. This length of wick 130

is determined by the space between the upper faces of the dies 121 and 153. Coacting with the latter is a knife 212 that is movable along the top surface of the die 153 to cut

- 5 the wick at the opening 124 in the die. The said knife is secured to an actuator 213 by means of screws 212a. A clamping plate 214 takes over the actuator to hold the knife down, and is fastened to the plate 140 by 10 screws 215. The said actuator is slidable in a recess 216 in the plate 140. To afford the requisite clearance for the plate 214 and the heads of screws 215, the under side of the rotatable feed table 101 is formed with a 15 series of concentric annular recesses 217 and 218. At its inner end the actuator is bent downwardly at 219 and 220 for clearance. Normally retracting the knife 212 is a tension coil spring 225 one end of which is connected to a fixed pin 226 and the other to the 20 said actuator by means of a hook 227.

To project the knife to cut the wick, the actuator 213 has mounted thereon a roller 228 which cooperates with a cam 229 that 25 is driven by the shaft 75. As shown in Figs. 11 and 12, the disk 77 on the shaft 75, carries a segment 230. The latter has arcuate slots 231 formed therein, permitting it to be adjustably secured by screws 232 to 30 the disk 77. The cam 229 may be formed integrally with the segment 230. To provide a large cam surface, a block 233 may be pinned to the integral cam portion referred to. It will thus be clear that rotation 35 of the shaft 75 causes a periodic cutting movement of the knife 212.

To permit the knife to be easily removed whenever necessary, the feed table 101 may be formed with a slot 235 extending there- 40 through, which slot may be brought into registry with the knife by rotation of the table.

Since the candles used herein have had the wick clips previously secured thereto, a 45 hammer 237 may be readily brought into operation after the wick has been threaded through the candle. The said hammer is mounted on a vertically reciprocating bar 238 which is guided in an arm 239 of the 50 bracket 107. To reciprocate said bar, a lever 240 is pivotally mounted on the bracket at 241, said lever being at its other end formed with a curved portion 242 that is received in slot bearing 243 in the said 55 bar. A horizontal plate 244 is movably guided along said slot, to adjust the clearance for the member 242, by means of a set screw 245. Engaging the lever 240 at 246 is a connecting rod 247 which extends down- 60 ward through a slot 248 in the circular flange 106, the bearing disk 102, and the plate 22 of the machine frame. The lower end of the connecting rod 247 is secured to a bearing 248 disposed between the disks 77 65 and 78, and journaled on the shaft 79. Ro-

tation of the latter may be avoided by a pin 249. Thus the rotation of the shafts 42 and 75, which operate in unison, causes the hammer 237 to reciprocate vertically.

To permit the hammer to be vertically 70 adjusted according to candles of varying lengths the shank 250 of the hammer has threaded engagement with an arm 251 of the bar 238. To retain the hammer in adjusted position, a locknut 252 may be used. 75

The hammer 237 includes an improved head 253 which is mounted on the shank 250 by a set screw 256. The said head has a bottom face which is of inverted conoidal form, and includes a plurality of radial recesses 257, which increase in depth and width from the center to the periphery thereof. When the hammer descends, the prongs in the wick clip are flattened to clinch the wick, and the projecting end of the latter is caused 85 to lie in one of the recesses 257, so that the wick is not severed by the impact with the hammer.

To automatically remove the finished candles from the feed table 101, an inclined 90 chute 260 is provided that is secured to the machine frame by an arm 261. To guide the candles into the chute, the latter is provided with a guide 262 that is disposed over the feed table 101 and is fastened to bracket 95 107. The guide 262 engages the candles one by one as the table rotates, and shifts the candles into the chute. From the chute the candles pass into any suitable receptacle.

The operation of the machine may be 100 briefly summarized as follows:

The operator places the candles in inverted vertical position on the dies 121, and as the shafts 42 and 75 rotate in unison, the latter through the pitman 84 causes a to and fro rotation of the gear 86 and thus reciprocates the rack bar 90, causing the feed table 101 to rotate step by step. This brings the candles successively to the wick threading means, and the latter begin to operate while the rack bar and the table actuating pawl 98 move idly backward. Thus, while the table is stationary, the pitman 182 moves the wheel 175 carrying the pawls 173 to turn the ratchet wheel 176 through a predetermined angle, to rotate the wheels 160 and 161 to feed the wick upward through the candle. Thereafter the cam 229 on shaft 75 causes the knife to sever the wick, while connecting rod 247 operated by cam 189 on the 110 shaft 42 brings the hammer 237 down to cause the wick clip to clinch the wick. On further rotation of the table 101 the completed candle is discharged down the chute 260. 115

I claim:

1. A device of the character described for threading a wick into a night candle having an ornamental upper surface, said device including a member having an opening and a similar surface to accurately center 120 125

65 and 78, and journaled on the shaft 79. Ro-

the candle in alinement with said opening in inverted, upright position of the candle without contacting the sides of the candle, and means to feed a wick through said opening and into said candle.

5 2. A machine of the character described, including means to support a candle, means to thread a wick into the candle, means to sever the wick, means to actuate the machine, and other means operated by a knot in the wick to cause the actuating means to stop.

10 3. A machine of the character described, including means to support a candle, means to thread a wick into the same, means to sever the wick, means to cause a clip on the candle to clinch the wick therein, drive means for the machine, and other means motivated by a knot in the wick to cause the drive means 20 to stop.

15 4. A machine of the character described, including a table rotatable about a vertical axis, said table being adapted to support a plurality of candles thereon, means to thread 25 a wick into the candles, means to sever the wick, a hammer to cause a clip on an end of the candle to grip the wick therein, the rotation of the table bringing the candles in succession to the wick threading means, and 30 a chute means coating with the table, said candles impinging a portion of the chute means and being discharged down the same due to the aforesaid rotation of the table.

In testimony whereof I affix my signature.
